UNITED STATES PATENT OFFICE.

CHRISTIAN GULERANSEN, OF CHICAGO, ILLINOIS, ASSIGNOR TO GULBRANSEN COMPANY, OF CHICAGO, ILLINOIS, A CORPORATION OF ILLINOIS.

PLAYER PIANO.

Application filed July 30, 1920. Serial No. 400,080.

My invention relates to pneumatically operated player pianos and is particularly concerned with improved means for transmitting the motion of the striking pneumatics to the respective hammers of the piano action.

My invention seeks maximum ease of playing and, consistently, the reduction to minimum or elimination of friction, in a simple compact assembly providing for properly advantageous mechanical leverage.

My invention is illustrated in the accompanying drawings, in which:

Figure 1 illustrates in side elevation a piano action with my improved player action applied thereto;

Figure 2 is a side elevational view on a larger scale, of my improved player action and the immediately associated parts of the piano action, parts being broken away and shown in section in order to reveal the interior construction;

Figure 3 is a rear elevational view of my improved player action;

Figure 4 is a fragmentary rear elevational view on a larger scale; and

Figure 5 is a fragmentary plan view.

The so-called pneumatic stack is preferably constructed almost entirely of wood.

The channel board, which extends substantially the entire length of the piano, is illustrated at 22. This board, as clearly illustrated in Figures 1 and 2, is disposed in a slightly oblique position, and is supported on brackets 22^a, 22^a secured to the piano bed 22^b. Secured to the rear face of the channel board 22 are the three valve shelves 87, 87, to the underside of each of which a series of striking pneumatics 96, 96 are secured, these striking pneumatics being relatively staggered, as illustrated in Figures 3 and 4, each comprising a stationary board 57, a movable board 55 hinged thereto at 58, and an intervening bellows cloth 56.

For each striking pneumatic, the shelf to which it is secured has communicating channels 99, 99 which are adapted to connect the interior of the striking pneumatic with the vacuum channel 104 from which air is exhausted by the operation of suitable exhaust bellows as is well known in the art.

The continuity of each pair of communicating channels 99, 99 is, however, controlled by a primary pneumatic valve 102 which operates alternately to connect the interior

of the corresponding striking pneumatic with the atmosphere and with the vacuum in the chamber 104. Each valve 102 is carried upon a valve post 98 which, in turn, is connected operatively with a diaphragm 97, the top of which is exposed to the vacuum in the chamber 104. The chamber below each diaphragm 97 is connected by means of a tracker channel 105 with the corresponding opening in the tracker bar of the player piano, as is well known in the art. A bleeder 106 is provided between each tracker channel 105 and the vacuum chamber 104, so that when the corresponding opening in the tracker bar is closed, air will be exhausted from the chamber below the diaphragm 97, thus balancing the pressures on opposite sides of the diaphragm and seating the valve 102 on the seat 102^a. Under this condition the vacuum is cut off and air is admitted to the striker pneumatic by way of the port 101, thus placing it in its normal distended position. When the corresponding opening in the tracker bar is opened to atmosphere, by reason of an opening in the note sheet coming in register therewith, air is admitted to the tracker channel 105 and, eclipsing the suction effect through the restricted bleeder 106, raises the diaphragm 97 against the lesser pressure on the other side. This action lifts the valve 102 away from its seat 102^a, shuts off the atmosphere at 101 and connects the vacuum chamber 104 with the interior of the striking pneumatic. Thus is the striker pneumatic collapsed.

The piano action itself may be of any approved form well known in the art and needs no detailed description here. Suffice it to say that when the keyboard end of any piano key 91 is depressed, the inner end, shown in Figures 1 and 2, rises, raising the corresponding abstract rod 93 through the intervention of the capstan screw 92, and swinging the wippen 93^a, which is connected thereto at 93^b about its pivot 93^c. This action is transmitted to the striker mechanism above as well known in the art. The wippen pivot 93^c is carried from a supporting bar 93^d, and the lower end of the connected abstract rod is guided by a swinging link 93^e pivoted thereto at 93^f and to the stationary support 93^g which, in turn, is secured to the supporting bar 93^h. Thus the abstract rod has up and down motion substantially parallel to itself.

For each striker pneumatic an actuating lever 50 is provided at the top of the pneumatic stack. Each lever 50 is located over and in central alignment with its respective striking pneumatic, as clearly shown in Figure 4. The levers 50, 50, all in horizontal alignment, are supported respectively, by hinges 51, 51 of flexible material clamped between the wooden strips 52 and 53 mounted 10 on top of the uppermost valve shelf 87 near the rear edge thereof. The levers 50, 50 extend rearwardly from their hinges so that the rearmost ends thereof will lie above the central rearward extensions 54, 54 on the 15 movable boards 55, 55 of the striker pneumatics and normally rest upon the cushion strip 61, of felt or some equivalent material, mounted upon the back stop rail 62, which in turn, is mounted on top of the stationary 20 boards of the uppermost row of striker pneumatics.

Between each movable pneumatic striker board, particularly the extension 54 thereof, and its corresponding actuating lever 50, a 25 spindle 59, conveniently of wood, is provided. At each end of this spindle, a pellet 60 of flexible material, such as leather, is secured, preferably by gluing. These pellets, in turn, are respectively secured, preferably 30 by gluing, to the under side of the actuating lever 50 and to the top side of the extension 54 on the movable board 55 of the striking pneumatic, as clearly illustrated in the drawings. The spindles 59, 59 are, of course, of 35 three different lengths, depending upon which row of striker pneumatics they reach to, as illustrated in Figure 4. When the striker pneumatics are in their normal position distended to the desired extent, the actuating levers 50, 50 rest upon the cushion strip 61. When a striker pneumatic is collapsed, its movable board 55, of course, swings upwardly into position approximately parallel with its stationary board 57 and 40 this action, then, is transmitted through the spindle 59 to its lever 50, the compressible character of the pellets 60, 60 making this motion possible notwithstanding the fact that they are secured to the parts 54 and 59. 45 Obviously, there is no friction in transmitting the motion of the movable board of the striker pneumatics to the actuating lever 50. The arrangement is extremely simple, not prone to get out of order, involving no lost 50 motion, or loose and rattling parts and making no noise.

The actuating levers 50, 50 are disposed, respectively, in vertical and transverse alignment with the wippens 93^a, 93^a, in the for-

ward end of each of which a contact button 60 55 is carried by way of the adjusting screw 94 in position to be engaged by the corresponding lever 50. The arrangement is such that when the wippen is in its lowermost position and when the actuating lever 50 65 is also in its lowermost position the contact button is so adjusted as just to contact with the end of the lever, as shown in Figures 1 and 2. The free end of each actuating lever 50 is rounded, this curve being carefully determined, and being substantially as illustrated, so that in the rising motion of the actuating lever 50, the contact between the end of the lever and the button 95 will be a 70 rolling one, thus eliminating friction also at 75 this point. Due to the position of the pneumatic stack relative to the wippen and abstract rod, it is clear how, from normal position, as shown in full lines in Figure 2, to the actuated position, shown in dotted lines, 80 this rolling contact will prevail, with an efficient transmission of the motion of the board 55 to the wippen 93^a.

It will be clear to those skilled in the art that, while I have illustrated and described 85 the preferred means for transmitting the motion of the boards 55, 55 to their respective levers 50, 50, a measure of the advantages of my invention might be secured by 90 operatively connecting these parts in some 90 way other than that which I have particularly referred to and I desire, therefore, that the scope of my invention shall be limited only as set forth in the appended claims.

I claim:

1. In a player piano, a striking pneumatic having a hinged board, a hinged actuating lever, a rigid connecting member having flexible portions at its ends secured to said board and lever respectively, the entire connection between said member and said board and lever being completed through said flexible portions.

2. In a player piano, a striking pneumatic having a hinged board, a hinged wooden actuating lever, and a wooden connecting spindle having a leather pellet glued to each end thereof, said pellets being also glued to said board and lever respectively, a piano action having a wippen in vertical and transverse alignment with said lever, and an adjustable contact member on said wippen, said actuating lever having a rounded top surface at its end for rolling contact with said member.

In witness whereof I hereunto subscribe my name this 27 day of July 1920.

CHRISTIAN GÜLBRANSEN.
